TRICYCLE

Filed Feb. 2, 1952

FIG. 1

FIG. 2

Inventor

Steve Sterancsak

UNITED STATES PATENT OFFICE

167,780

TRICYCLE

Steve Sterancsak, Clifton, N. J.

Application February 2, 1952, Serial No. 18,346

Term of patent 3½ years

(Cl. D34—15)

To all whom it may concern:

Be it known that I, Steve Sterancsak, a citizen of the United States, residing at Clifton, in the county of Passaic and State of New Jersey, have invented a new, original, and ornamental Design for a Tricycle, of which the following is a specification, reference being had to the accompanying drawing, forming part thereof.

Figure 1 is a perspective view of a tricycle, showing my new design.

Figure 2 is a top plan view thereof.

I claim:

The ornamental design for a tricycle, as shown.

STEVE STERANCSAK.
